UNITED STATES PATENT OFFICE.

CHARLES A. GASS, OF RED ROCK, ARIZONA.

PUMPING-JACK.

1,191,780.

Specification of Letters Patent. Patented July 18, 1916.

Application filed August 4, 1915. Serial No. 43,549.

To all whom it may concern:

Be it known that I, CHARLES A. GASS, a citizen of the United States, and a resident of Red Rock, county of Pinal, State of Arizona, have invented certain new and useful improvements in Pumping-Jacks, of which the following is a specification.

My invention relates more particularly to pumping mechanism adapted for duplex pumps wherein two pistons are reciprocated in the same cylinder for lifting water in a substantially continuous stream; this being accomplished by having one or the other of the pistons continuously in operation.

Various mechanisms have been devised for operating double piston pumps adapted to accomplish this purpose, but these mechanisms usually embody cams and gears of more or less complex nature.

The object of my device is to accomplish these results with a very few, simple and direct linkage connections between the cranks and the pump rods.

A further object of my invention is to so arrange said linkage connections that the proportion of each revolution of the crank during which the corresponding pump rod is lifting shall be substantially greater than the proportion during which the pump rod is being depressed.

A still further object of my invention is to so proportion the several linkage connections that the rate at which the individual pump rods are lifted shall be substantially uniform from the beginning to the end of every stroke instead of continuously increasing from the beginning of the stroke to its middle point and then continuously decreasing for the remainder of the stroke as is common in most arrangements.

In the arrangement herein disclosed, the parts are so proportioned that one pump begins to pick up its load on the upper stroke about 20° earlier in the revolution of its crank than does the other pump. To off-set this difference and to cause the overlap of the lifting strokes to be the same at both ends, I preferably off-set the crank belonging to the pump which picks up latest, by 10° (half of the difference of pick-up) toward the crank of the first pump. In other words the crank of the second pump is arranged to follow the crank of the first pump 170° later while the crank of the first

pump follows the crank of the second pump 55° later.

One form of my mechanism is illustrated in the accompanying drawings in which—

Figure 1 represents a vertical sectional elevation, the section being taken on the line 1—1 of Fig. 2; Fig. 2 is a rear elevation of the pumping jack; Fig. 3 is a vertical section through the middle of the machine representing the cranks and associated parts in the opposite position from that shown in Fig. 1 and Fig. 4 is a diagrammatic view of the mechanism.

Referring to the drawings 1 represents the frame of the machine which may consist of two upright brackets spaced apart and adapted to support the mechanism including slideways 2 which are secured to each side of the frame 1 and upon which crossheads 3 and 4 are adapted to reciprocate up and down during the pumping operation. The upper crosshead 3 is preferably connected with the pump rod 5 which latter is adapted to slide in the concentrically arranged pipe or tubular pump rod 6 which is secured to the lower crosshead 4 substantially as indicated in the drawings. This form of pump, having concentrically arranged pump rods is well known in the art and therefore it is not necessary to further describe it and it is not here completely shown.

For operating the two pump rods I mount in the frame a crank shaft 7 provided with the usual fly wheel 8, said crank shaft, in the present instance, being provided with two substantially oppositely disposed sets of cranks, one crank 7^a at the center and the other crank 7^b being divided or in duplicate having a half on each side of the center, the oppositely disposed cranks being as previously indicated relatively displaced circumferentially so that one is in advance of the other about 190° . To each crank I connect, directly by means of a boxing 9, a walking beam 10 which is fulcrumed at 11 to the upper end of a link 12 pivoted to a rod 13 supported in the frame 1 of the machine the links 12 thereby acting as floating fulcrum supports for the walking beams. The outer ends of the walking beams 10 are pivotally connected at 10^a with links 14 and 15, the latter (15) being connected to the crosshead 3 of the upper pump rod 5, while the former (14) is connected to the lower cross-

head 4 on the pipe or tubular pump rod 6. The walking beams may be constructed in any suitable manner either of a single piece or two pieces as illustrated in the drawings 5 and may be connected to the cranks in any suitable manner. The cranks 7^a are oppositely disposed from the cranks 7^b and the walking beams connected therewith are adapted to operate the lower crosshead 4 by 10 means of the links 14 while the crank 7^b, by means of its walking beam and the links 15, is adapted to operate the upper crosshead 3. It will be seen from this arrangement that when the crank shaft 7 is rotated 15 the walking beams are not only rocked about the fulcrum 11 but are bodily reciprocated so that the free ends of the walking beams are constrained to pass through a compound curved path substantially as indicated at B in Fig. 4 of the drawings.

Referring more particularly to Fig. 4 it will be seen that as the cranks rotate counter-clockwise, as indicated by the arrows, the outer or free end A' of the walking beam A 25 will be moving clockwise upwardly along the curve B while at the same time the outer end C' of the walking beam C will be moving clockwise downwardly. It will thus be seen that the point D, which represents the 30 connection of the link 15 with the upper crosshead 3, will be moving upward to lift the pump rod 5 while the point E, representing the connection between the link 14 and the lower crosshead 4, will be moving downward 35 and thereby carrying the piston connected with the pipe rod 6 downward to get a fresh hold on the stream of water. It will be observed, by tracing the movements of the parts in Fig. 4, that the overlapping 40 of the strokes, will give substantially a continuous flow. The dotted lines F in Fig. 4 indicate the extremes of the movement of the floating fulcrum links 12 of the walking beams during a complete rotation of the 45 cranks. As previously pointed out the crank 7^a is preferably approximately 190° in advance of the crank 7^b while during the rotation of the crank shaft the crank 7^b is lifting during about 200° of circumferential 50 movement while the crank 7^a utilizes about 180° for the lifting movement. This overlap of 20° is adapted to provide a substantially continuous flow of the stream being lifted by the pump. This linkage arrangement 55 is adapted to carry the pump rods up and down in a more nearly uniform manner so that, at the extremes of movement, the pump rods are gradually stopped and started in the opposite direction, thereby relieving the mechanism of any undue jars or strains.

While I have shown a preferable construction and arrangement of the parts it will be understood that the connecting links from 60 the walking beams may extend in the same

direction either up or down if desired, or to meet any special construction or adaptation of my device. Obviously, also, the relative positions of the oppositely disposed cranks may be 180° or other suitable angle to give 70 any modification or variation of the lap of the plungers.

It will be understood that suitable counterbalancing devices may be employed to counterbalance the pump rods and other 75 moving parts of the mechanism and various modifications of the specific details of the mechanism may be made without departing from the spirit and scope of my invention.

I claim:

1. In a pumping jack the combination with pump rods of a crank shaft having oppositely disposed cranks, a walking beam having one end directly pivoted to each of said cranks, a floating fulcrum for each 80 walking beam, and links connecting the outer ends of the respective walking beams to the pump rods.

2. In a pumping jack the combination of a frame, a crank shaft having oppositely disposed cranks revolubly mounted therein, a walking beam having one end directly pivoted to each of said cranks, links pivotally supported by said frame and pivotally connected to the respective walking beams 85 to form floating fulcrums therefor, a pair of pump rods, concentrically arranged, and links connecting the outer ends of said walking beams to the respective pump rods whereby the latter are adapted to be reciprocated simultaneously in opposite directions.

3. In a pumping jack the combination of a frame, a crank shaft having oppositely disposed cranks revolubly mounted therein, 105 a walking beam connected directly at one end to each of said cranks, a rocking link for each walking beam adapted to form a floating fulcrum therefor, said links being supported by the frame, vertically disposed 110 sideways on said frame, crossheads slidably mounted thereon, one at each end, a pump rod connected to each crosshead, said pump rods being concentrically arranged, and connecting links between the outer ends 115 of said walking beams and the respective crossheads whereby said pump rods are adapted to be reciprocated simultaneously in opposite directions.

4. In a pumping jack the combination 120 with pump rods of a frame, a crank shaft having oppositely disposed cranks mounted in said frame, a walking beam having one end directly pivoted to each of said cranks, links connecting the outer ends of said walking beams to the respective pump rods, and links pivotally supported by the frame and pivotally connected to the respective walking beams at points between the crank and pump rod link connections, the parts being 125

so proportioned and dimensioned that the connection between the walking beam and the link going to the pump rod will trace a compound curved path substantially as described.

5. In a pumping jack the combination with pump rods of a crank shaft having oppositely disposed cranks, a walking beam having one end directly pivoted to each of
10 said cranks, links connecting the outer ends of the respective walking beams to the pump rods and a floating fulcrum for each walk-

ing beam located at a point between its ends, the parts being so proportioned and dimensioned that the rate of stroke of each pump 15 is substantially proportional to the rotation of the crank and the time during which the individual pumps lift is substantially in excess of the time during which they are depressed.

20 In testimony whereof I have hereunto set my hand.

CHARLES A. GASS.
